LINUS YALE, JR., OF SHELBURNE FALLS, MASSACHUSETTS.

Letters Patent No. 71,110, dated November 19, 1867.

IMPROVEMENT IN BURGLAR-PROOF SAFES.

The Schedule referred to in these Letters Patent and making part of the same.

TO ALL WHOM IT MAY CONCERN:

Be it known that I, LINUS YALE, Jr., of Shelburne Falls, in the State of Massachusetts, have invented a new and useful Improvement in Burglar-Proof Safes; and I do hereby declare that the following is a full, clear, and exact description thereof, reference being had to the accompanying drawings, making part of this specification, in which—

Figure 1 is a front elevation,

Figure 2 a vertical, and

Figure 3 a horizontal section, taken at the lines A a and B b, of fig. 1.

The same letters indicate like parts in all the figures.

Burglars have succeeded in forcing open iron safes by driving series of wedges between the edges of the door and the surrounding framing, each successive series of wedges being thicker, and various plans of construction have been tried to guard against such modes of opening; but, so far as I am informed, without success.

I have invented a method of construction which is an effectual protection against such modes of forcing open safes, and my said invention consists in making the edges of the door, or of the door and surrounding frame, of a bending or equivalent form, to leave an open wedged-formed space all around between the edges of the door and the surrounding frame, and extending to, or nearly to, the surface of the rebate of the door-frame, so that such open space shall present sloping sides so great, say as great as the slope of wedges, that the edges of wedges, when attempted to be driven, shall strike against and be arrested by the face of the rebates of the door-frame against which the door shuts.

In the accompanying drawings, which represent the door-frame and door of an iron safe or vault, the door a is hinged in the usual or any suitable manner to the frame b, into and against which it shuts. The sides, top, and bottom of the door-frame are, as usual, made with one or two rebates, the front face of which, as at c, is parallel with the plane of the door when closed, and the edges of these rebates are bevelled outward, as at d, and the edges of the door, sides, top, and bottom, from the inner face of the rebate, is bevelled, as at e, the reverse of the bevels of the door-frame. In this way I form V-shaped open spaces, g g g g, along the four edges of the door between it and the door-frame, and extending from the face of the rebate in the door-frame to the outer surface of the door, into which wedges cannot be driven, as it will be obvious that wedges made as blunt as the said open spaces, would be stopped by their points coming into contact with the face of the rebates in the door-frame, and, if made more blunt than the said open spaces, the required force for breaking open a safe could not be obtained.

It will be obvious that the form of the said open spaces, and the angle of inclination of the sides thereof, may be varied, without departing from the character of my said invention; and, although I have above described the said open spaces as being formed by bevelling the edges of the door and of the door-frame in opposite direction, I do not wish to be understood as limiting my claim of invention thereto, as it will be obvious that the same result in kind can be attained by bevelling the edges of the door only or of the door-frame.

What I claim as my invention, and desire to secure by Letters Patent, as a means of preventing safes and vaults from being forced open by wedges, is—

Making an open space between the edges of the door and the door-frame, substantially as and for the purpose specified.

LINUS YALE, JR.
